UNITED STATES PATENT OFFICE.

SLAUGHTER W. HUFF, OF BROOKLYN, NEW YORK.

DRAWN-LINK ELECTRIC FUSE.

1,228,924.

Specification of Letters Patent.

Patented June 5, 1917.

Application filed August 21, 1914. Serial No. 857,904.

To all whom it may concern:

Be it known that I, SLAUGHTER W. HUFF, a citizen of the United States, residing in the borough of Brooklyn, in the city and State of New York, have invented certain new and useful Improvements in Drawn-Link Electric Fuses, of which the following is a specification.

My invention relates to fuses constructed for interpolation in an electric circuit and embodying a conducting link with relatively low fusing point and with a current-carrying capacity below that of apparatus served by the circuit and required to be protected from the destructive effects of overloading. More specifically, the invention relates to so-called cartridge fuses in which the fusible link is incased to avoid damage from arcing usually incident, to greater or less degree, to the so-called blowing of the fuse, and in which the link is embedded in finely divided refractory material to dissipate the arc; and especially to larger capacity fuses of this type wherein it is very desirable to restrict the current-gaging dimension of the link to a relatively short intermediate portion of the link so as to localize the fusing point as far as practicable from the conducting ends of the casing, and in which the remainder of the link body extending beyond the reduced portion or gaging reach, is proportioned to afford a carrying capacity that will insure against undue heating or detracting from the localizing effect of the reduced middle portion.

Heretofore it has been customary to make the links of these intermediately reduced fuses, of thin ribbon-like metal having its intermediate portion reduced in conducting capacity to a greater or less degree, as may be required, by notching the links inward from the edges or punching out portions thereof. But considerable difficulty and expense have generally been involved in securing uniformity of capacity in links of this type, owing to wide variations in the density and texture of stock metal which the market affords. Moreover, such links

are expensive to use in manufacture because of complications incident to assembling them with other parts of the fuse.

Attempts have been made to remedy these difficulties by the use of bar-links of rectangular section, but with only partial success so far as concerns the difficulties and consequent expense of manufacture. It has been proposed to use drawn metal links in the form of round wire, but only for the smallest capacity fuses, where localizing of the fusing point and holding down temperatures in the intermediate portions is comparatively unimportant. Wire has not been used for the larger capacity fuse links, because no way has heretofore been known to satisfactorily localize the heat therein and develop an intermediate fusing point.

I have discovered that fuse links made of a drawn body of metal are particularly desirable for the larger capacities, because of uniformity of dimensions, texture and conductivity which is insured by the wire-drawing process as a method of producing the metal stock. I have also discovered by experiment that if drawn metal bodies, such as wire, having a conducting capacity sufficiently in excess of the maximum current to be carried, to avoid excessive heating throughout the main body of the wire, be employed for a fuse link and an intermediate portion of such a body be reduced in section, by cutting away a portion of the dimension transverse to the direction of drawing, the portion, of reduced transverse dimension, which remains will be of the same uniform texture and conductivity as the main body of metal, and can be relied upon to afford an accurate carrying capacity in proportion to the metal left in the section, so that for the purpose of accurately producing fuses of predetermined capacity, it is merely necessary to gage the cut or reduction that is made in the transverse dimension; and this being in turn brought under accurate control by the provision of a suitable tool whose work can be regulated at will, the production in large numbers of fuses uniform in gaged capacity and from

metal stock purchased in the open market, can be carried on with certainty without the expense of re-conditioning or re-gaging the metal. These conditions become all the 5 more important in view of the growing demand for fuses conforming to special conditions or specifications.

The present invention will be fully understood upon reference to the accompanying 10 drawing, in which—

Figure 1 is an axial sectional view of a complete fuse constructed in accordance with the present invention and having in addition thereto a subsidiary or indicator 15 fuse;

Fig. 2 is a view similar to Fig. 1, showing a modification in the connections between the fusible link and the end caps of the fuse; and

20 Figs. 3 and 4 are sectional views showing modified forms of fuse links made of drawn metal and having intermediate portions reduced by removal of a portion of the metal.

1 represents the case of the fuse, 2 the 25 fusible link, 3 the end caps secured to the case by means of pins 3^a, and 4 the indicator wire which has its ends lapped at 4^a over the ends of the case 1, so as to be brought into contact with the end caps 3, 30 while an intermediate portion of the indicator wire extends diametrically across a bore 5 in the case 1, containing an explosive charge 6 which is backed up by the breech closure 7, preferably formed of a 35 strip of fiber cemented to the inner face of the case, and confined on the outside by a wad 8, which may be conveniently provided from plastic material, such as plaster of Paris. The details of this indicator are 40 not claimed in this application, but form the subject matter of a copending application, Serial No. 857,903, of even date here-with.

The intermediate portion of the link 2 45 is cut away so as to leave a reduced portion 2^a whose sectional area will correspond to and accurately gage the maximum current to be conveyed, while the main portions of the link 2 lying between the reduced portion 2^a and the ends of the fuse, are of 50 sufficient capacity to carry this fusing current without undue heating. This fusible link is constructed of a drawn body of metal and is, therefore, very accurate in 55 dimension, texture and conductivity, so that by accurately gaging the extent of the cut at the intermediate portion, and consequently determining the transverse dimension of the reduced portion 2^a that remains, 60 the carrying capacity of the link can be determined to a nicety. Novel means are provided for securing the link 2 in the ends of the fuse. Fig. 1 shows headed sleeves or thimbles 9 introduced through central

openings in the depressed portions 3^b of the 65 end caps 3 and surrounding a sufficient proportion of the ends of the link to insure arrest of the burning action before it reaches the end caps. The depressed portions of the end caps, the thimbles 9 and the ends of the 70 link are all firmly united by solder bodies 10 poured into the spaces between the parts as a step in the manufacture of the fuse. According to Fig. 2, the ends of the link 75 are secured directly in the central openings of the depressed portions 3^b of the end caps by means of the solder bodies 10, which are found in most instances sufficient to arrest the burning before it reaches the 80 end caps. The end caps are preferably provided with the usual relief openings 3^c closed by paper or other disks 11, to prevent an escape of the refractory material 85 with which fuses of this type are usually filled.

Figs. 3 and 4 show another method of providing a drawn metal fuse body with an intermediate portion reduced and made up of the drawn metal of uniform texture and conductivity; the reduced portion 2^{xx} 90 representing the original caliber of a wire forming the central portion of the link, and the increased diameter for reducing the heating effect beyond the reduced fusing point being provided by drawn metal 95 jackets 2^x intimately associated with the central core 2. The fuse link constructed in this way may be introduced into the fuse, as is the link 2 in Fig. 2; or, as suggested in Fig. 4, such a composite link may be provided with the thimbles 9 as a means of reinforcing the ends next to the cap in the manner already described with reference to Fig. 1.

In another aspect of the construction 105 shown in Fig. 3, the jackets 2^x may be regarded as prolongations of the sleeves or thimbles 9 and they may, if desired, be provided with the end flanges with which said thimbles are shown in Figs. 1 and 4. The 110 sleeves 2^x would, in that case, serve the dual purpose of raising the capacity of the main portions of the link and reinforcing the link physically as well.

I claim:—

1. In an electric fuse, a conducting link 115 constructed of drawn wire having an intermediate portion cut away transversely through a portion of its thickness and thereby reducing its dimension transverse 120 to the direction of drawing and leaving a reduced portion of the original drawn metal with its structural character unchanged, corresponding in sectional area to the carrying capacity desired.

2. In an electric fuse, a link constructed 125 of metal of round section drawn in the direction of the length of the link; the inter-

mediate portion of said link being cut away from the cylindrical surface inward and thereby leaving a semi-cylindrical section of less transverse dimension than the end portions thereof, but of the same structural character.

5 The foregoing specification signed at

Brooklyn, New York, this 31st day of July, 1914.

SLAUGHTER W. HUFF.

In presence of—

HELEN SEGELBACHER,

JOHN A. THAKE.
